(57) **CLAIM**

The ornamental design for a microphone, as shown and described.

DESCRIPTION

FIG. 1 is a perspective view of the top, front and left side of a microphone showing our new design;

FIG. 2 is a perspective view of the bottom, front and right side thereof;

FIG. 3 is a top plan view thereof;

FIG. 4 is a bottom plan view thereof;

FIG. 5 is a front elevational view thereof, with the rear elevational view being a mirror image;

FIG. 6 is a right side elevational view thereof, with the left side elevational view being a mirror image;

FIG. 7 is a sectional view thereof along sectional line 7—7 in FIG. 3; and,

FIG. 8 is a sectional view thereof along sectional line 8—8 in FIG. 3.

The portions shown in broken lines are for illustrative purposes only and form no part of the claimed design.
